UNITED STATES PATENT OFFICE

JOHN B. D. THOMPSON, OF UNION CITY, NEW JERSEY, ASSIGNOR TO AMERICAN CAR AND FOUNDRY COMPANY, OF NEW YORK, N. Y., A CORPORATION OF NEW JERSEY

ARTICULATED CAR

Application filed January 3, 1931. Serial No. 506,385.

This invention relates to articulated cars of the type in which adjacent car body end portions are supported by a single truck known in the art as a pivot truck.

One object of this invention is the provision of a new and improved articulated joint for railway cars.

Another object of this invention is the provision of an articulated car in which a pair of relatively movable bolster sections are provided for supporting the adjacent end portions of two car bodies; the said bolster sections supporting a truck center plate with which body center bearings are engaged.

Still another object of this invention is the provision of an articulated car having means for supporting a foot plate by the car truck.

A further object of this invention is the provision of an articulated joint in which excessive relative sidewise and vertical shifting is prevented.

A still further object of this invention is the provision of a multi-part body center casting for an articulated car.

Another object of this invention is the provision of a multi-part body center casting for an articulated car in which the parts thereof may be easily and quickly separated whereby to permit a quick and easy separation of adjacent car bodies.

Other objects and advantages of this invention will be apparent from the following description taken in conjunction with the accompanying drawing in which:

Fig. 1 is a top plan view of certain parts of the end portions of two adjacent car bodies, the view having certain parts broken away, other parts shown in section, and still other parts removed to more clearly disclose the invention.

Fig. 2 is a sectional view showing the end portions of two car bodies and the articulation therefor, together with a sectional view of a truck bolster and truck center plate, and

Fig. 3 is a sectional view on the line 3-3, of Fig. 2.

Referring now more particularly to the drawing, the present invention is designed to couple together the adjacent end portions of two car bodies, portions of which are shown

more or less conventionally and diagrammatically at A. It is to be understood that only such parts of the bodies as are necessary for an understanding of the present invention are illustrated, as the specific construction of the major portions of the car bodies forms no part of the present invention.

The bodies are provided with suitable underframes, including in the present instance, spaced channels 2 defining center sills between which, at the ends thereof, are arranged retaining castings 4 secured to said channels by suitable fasteners such as rivets 6; the castings being formed with horizontally arranged sockets 8. The rear ends of the castings 4 are closed by walls 10, and abutment walls 12 are provided adjacent to but spaced from the rear walls 10 as shown clearly in Figs. 1 and 2. The retainer castings 4 form parts of body center castings indicated generally at 13. These body center castings also include inner castings 14, hollow as shown clearly in Fig. 2 and of such size as to nicely fit the before mentioned sockets 8 and, so far, are similar to the castings shown in patent to A. E. Ostrander, et al. No. 1,726,667. As clearly shown in Fig. 2 the inner castings 14 are secured in the sockets by means of pins 16 which extend through the retainer castings and through said inner castings, and the forward ends of the inner castings project beyond the forward ends of the retainer castings and are provided with depending projections 18, having convex bearing surfaces 20 which are in the form of a portion of a sphere the center of which is substantially midway between the ends of the car bodies. These bearing portions engage in a bearing block 22 carried by a truck center plate 24; the bearing block having concave bearing surfaces 23. The upper end of each projection 18 is arranged in a horizontal plane lower than the upper walls of the castings 14 to provide horizontally arranged shoulders 25, the purpose of which will be hereinafter described. The projections 18 are shown as being formed integral with the remainder of the inner castings 14 but obviously this is merely by way of example as they may be formed separately and

attached to the forward ends of the castings 14 in any suitable manner if desired. In the present instance the forward end portions of the castings 14 include the projections and 5 said forward end portions are vertically recessed as at 26 and are arranged in close proximity to and partially encircle a hollow upstanding sleeve 28 formed with and preferably arranged concentrically with respect 10 to the main portion 30 of the bearing block 22.

The bearing block 22 is mounted on a truck bolster indicated generally at 32 and formed of similar but oppositely disposed sections 34 15 and 36 respectively. The bolster 32 is substantially identical with that shown in patent to Ostrander heretofore mentioned and no specific claim is being made to the construction thereof.

20 The bearing block 22 is carried by a truck center plate 24 which is circular in shape and provided with a base 38 having depending oppositely arranged flanges 39 which fit over flanges 41 of the bolster whereby the center 25 plate 24 is positioned.

30 The center plate further includes an upstanding annular marginal flange 42 and a concentrically arranged guide flange 44 which extends into the sleeve 28, the latter defining a pin receiving opening 46 as hereinafter pointed out. The bearing block 22 is retained in position by the flange 42 but it will be apparent that the flange 44, being fitted into the sleeve 28 will also serve to retain the bearing block 22 in its proper position.

35 To permit passage from one car body to the other it is necessary to provide a means which bridges the space between adjacent end portions of the car bodies, and in the present invention a foot plate 48 is provided for this purpose. In practice the foot plate is circular as shown clearly in Fig. 1 and the present invention contemplates a means for supporting the foot plate from the truck and more particularly from the truck bolster 32 whereby it is maintained in a substantially fixed position relative to adjacent end portions 40 of the car bodies. As shown clearly in Fig. 2 a pin 50 is provided which extends through the sleeve 28 and guide flange 44 and then between the bolster sections 34 and 36; the webs of the latter being provided with vertically arranged recesses 52 substantially 45 midway between the ends of said sections which define a substantially vertical recess as will be apparent. The lower end of the pin 50 extends through a collar 54 having trunnions 56 engaged in openings formed in the bolster webs whereby the pin is retained against vertical shifting. Secured to the end of the pin, for an obvious purpose, is a nut 58.

50 In the present invention the pin 50 is utilized to support the foot plate as well as to

prevent excessive relative vertical shifting of the car bodies. The pin 50 is provided with a head 60 which rests upon the upper edge of the sleeve 28 and overlaps the shoulders 25 of the projections 18. Secured to the head 60 in any suitable manner is a bracket 62 having attaching flanges 64 to which latter the foot plate 48 is secured in any suitable manner as by welding or riveting. The pin 50, adjacent the head 60 is of a diameter such as to substantially engage the inner walls of the sleeve 28 and the lower end of pin 50 is reduced in diameter whereby to extend through the guide flange 44 and the recess defined by the oppositely arranged recesses 52 in the bolster section webs.

55 From the above description it is believed that the construction will be fully apparent to those skilled in the art. In use, the car body end portions may swivel relative to each other and because of the specific conformation of the bearing block and lower portions of projections 18, the car bodies will be prevented from excessive relative sidewise shifting. Excessive relative vertical shifting of the car bodies is prevented due to the overlapping of the head 60 with the shoulders 25 of the projection 18; the pin 50 being retained in a substantially fixed position at all times due to the trunnions 56. To disassemble the 60 joint of the present invention, the nut 58 is removed, whereupon the pin 50 with its associated foot plate 48 may be lifted away from the remainder of the structure whereupon either or both of the car bodies may be removed from engagement with the truck by elevating the end portions thereof to disengage the projections 18 from the bearing block.

65 It will be apparent that the upper end of the pin 50, arranged in the sleeve 28 serves to transmit buffing shocks from one car body to the other or from the car bodies to the truck, while pulling stresses are transmitted from one body to the truck and from one body to the other through the projections 18, the bearing block, and then the truck center plate and truck bolster.

70 The drawing herein illustrates one embodiment of the invention but it is to be understood that they are for illustrative purposes only and various changes in the form and proportions of the construction shown may be made within the scope of the appended claims without departing from the spirit of the invention.

75 What is claimed is:

1. In an articulated car comprising a plurality of car bodies, a truck having a center plate, a bearing member carried by the center plate and provided with an annular concaved recess, bearing elements at the adjacent end portions of said car bodies having their bearing surfaces complementary to and supported in the annular recess, a spacing element ex- 80 85 90 95 100 105 110 115 120 125 130

tending upwardly from the bearing member for retaining the bodies in spaced relation, and means extending from the center plate and cooperating with the said spacing element for restraining the bearing member against horizontal shifting.

2. In an articulated car comprising a plurality of car bodies, a truck arranged beneath the adjacent end portions of said bodies and provided with a center plate, a bearing member carried by the center plate, retainer castings secured to the adjacent end portions of said car bodies, body castings arranged in and removably secured to the said retainer castings and provided with bearing elements at their forward ends, the bearing surfaces of said elements being complementary to and supported in the before mentioned bearing member, a spacing element extending upwardly from the bearing member and arranged between the said bearing elements for retaining the bodies in proper spaced relation, and means formed with the center plate and cooperating with the said spacing element for restraining the latter against horizontal shifting.

3. In an articulated car comprising a plurality of car bodies, a truck having a center plate, a bearing member supported by the center plate, bearing elements at the adjacent end portions of said bodies engaged with the bearing member, the bearing surfaces of said elements being in the form of a portion of a sphere, and a rigid element arranged between and cooperating with the bearing elements and connected to the truck whereby to restrain the bearing elements against vertical shifting, a portion of said element defining buffing means.

4. In an articulated car comprising a plurality of car bodies, a truck having a center plate, a bearing block supported by the center plate and provided with a concentrically arranged guide, bearing elements at the adjacent end portions of said bodies having portions partially encircling the guide, the bearing surfaces of said elements being in the form of a portion of a sphere the center of which is arranged in the line of buffing shocks to which the bodies are subjected.

5. In an articulated car, a pair of car bodies, a truck having a center plate, a combined bearing block and body bearing guide supported by the center plate, telescopically arranged body center castings secured to the adjacent end portions of the bodies and provided with depending bearing elements arranged adjacent to the body bearing guide for relative horizontal swiveling movement, and a pivot pin extending through the body bearing guide into a truck part for retaining the bodies against relative vertical shifting.

6. In an articulated car, a plurality of car bodies, a truck bolster having a center plate

provided with a concentrically arranged guide flange, a bearing block supported in the center plate and restrained against horizontal shifting by said guide flange, body bearings engaged in the bearing block, and a combined pivot pin and buffing element arranged intermediate the adjacent end portions of the bodies and connected to the bolster.

7. In an articulated car, a pair of car bodies, a truck bolster having a center plate, a bearing block in said center plate provided with a concentrically arranged guide sleeve, body connection castings secured to the adjacent end portions of the bodies and having depending projections at their forward ends which partially encircle the said guide sleeve, and a foot plate lapping the adjacent end portions of said bodies and supported by the guide sleeve.

8. In an articulated car, a body connection casting comprising a retaining casting, an inner casting connected thereto and freely removable therefrom, the forward end of said inner casting being provided with a depending body bearing having the bearing surfaces thereof in the form of a portion of a sphere.

9. In an articulated car, a body connection casting comprising a retaining casting, and a second casting telescopically arranged with respect to the retaining casting and provided at its forward end with a body bearing having an arcuate front surface, the bearing surface of said body bearing being in the form of a portion of a sphere.

10. In an articulated car, a body connection casting comprising a retaining casting, a second casting telescopically arranged with respect to the retaining casting and having a longitudinally recessed projection at its forward end defining a body bearing, the bearing surface thereof being in the form of a portion of a sphere.

11. In an articulated car, a pair of car bodies, a truck bolster having a center plate, a bearing block carried by the center plate and having an upstanding guide sleeve, body bearing elements engaged in said bearing block and partially encircling the sleeve, a combined pivot pin and buffing element arranged in the sleeve and connected to the bolster, said pin having a head overlying the body bearing elements whereby to restrain the bodies against excessive relative vertical shifting, and a foot plate bridging the space between the adjacent end portions of the bodies and supported by the head of the pivot pin.

12. In an articulated car, a pair of car bodies, a truck bolster, a center plate on the bolster provided with a concentrically arranged upstanding guide, a bearing block supported by the center plate and fitted around the guide, said bearing block hav-

- ing an upstanding concentrically arranged sleeve into which the before mentioned guide extends, body bearing elements at the adjacent end portions of the bodies supported for horizontal swiveling movement in the bearing block and partially encircling the sleeve, and a buffer element positioned in the sleeve and extended into and connected to the bolster.
- 10 13. In an articulated car comprising a plurality of car bodies, a truck for supporting the adjacent end portions of the bodies, a truck bolster, a center plate supported by the bolster, a bearing element carried by said center plate, body bearings at the adjacent end portions of said bodies having their bearing surfaces in the form of a portion of a sphere the center of which is above the bearing surface and which defines the center of horizontal swiveling of the bodies, a spacer extending upwardly from the bearing element, means on the center plate cooperating with the spacer for restraining the bearing element against horizontal shifting, and a pivot pin for retaining the bearing element, center plate and bolster in assembled relation and for restraining the bodies against excessive relative vertical shifting.
- 20 14. In an articulated car comprising a plurality of car bodies, a truck for supporting the adjacent end portions of the bodies, a truck bolster, a center plate supported by the bolster, a bearing element carried by said center plate, body bearings at the adjacent end portions of said bodies having their bearing surfaces in the form of a portion of a sphere the center of which is above the bearing surface and which defines the center of horizontal swiveling of the bodies, a spacer extending upwardly from the bearing element, means on the center plate cooperating with the spacer for restraining the bearing element against horizontal shifting,
- 25 45 and a pivot pin for retaining the bearing element, center plate and bolster in assembled relation.

In witness whereof I have hereunto set my hand.

JOHN B. D. THOMPSON.
